US00D882884S

(12) **United States Design Patent** (10) **Patent No.:** **US D882,884 S**
(45) **Date of Patent:** **** Apr. 28, 2020**

(54) **RETRACTABLE DOG LEASH**

(71) Applicant: **Shenzhen Xcho Technology Limited**,
Shenzhen (CN)

(72) Inventors: **Zhangli Lan**, Shenzhen (CN); **Yukun Yang**, Shenzhen (CN); **Jian Li**, Shenzhen (CN)

(**) Term: **15 Years**

(21) Appl. No.: **29/660,605**

(22) Filed: **Aug. 22, 2018**

(30) **Foreign Application Priority Data**

Mar. 20, 2018 (CN) 2018 3 0104040

(51) **LOC (12) Cl.** **30-04**

(52) **U.S. Cl.**

USPC **D30/153**

(58) **Field of Classification Search**

(57) **CLAIM**

The ornamental design for a retractable dog leash, as shown and described.

DESCRIPTION

FIG. 1 is a front elevational view of a retractable dog leash showing our new design;
FIG. 2 is a rear elevational view thereof;
FIG. 3 is a left side view thereof;
FIG. 4 is a right side view thereof;
FIG. 5 is a top plan view thereof;
FIG. 6 is a bottom plan view thereof;
FIG. 7 is a top, rear, left side perspective view thereof; and,
FIG. 8 is a top, front, right side perspective view thereof. The broken lines depict portions of the article that form no part of the claimed design.

1 Claim, 5 Drawing Sheets
